UNITED STATES PATENT OFFICE

102,467

DESIGN FOR A LIQUID SPRAYER

Fred Lindell, Chicago, Ill.

Application November 7, 1936, Serial No. 65,768

Term of patent 3½ years

To all whom it may concern:

Be it known that I, Fred Lindell, a citizen of the United States, residing at Chicago, in the county of Cook and State of Illinois, have invented a new, original, and ornamental Design for Liquid Sprayer, of which the following is a specification, reference being had to the accompanying drawing, forming a part thereof.

Fig. 2 is a top plan view thereof.

The dominant features of my design reside in the portions shown in full lines.

I claim:

The ornamental design for a liquid sprayer substantially as shown and described.

FRED LINDELL.
